(57) **CLAIM**

An ornamental design for an electronic device display screen with graphical user interface for financial instrument tracking, as shown and described.

DESCRIPTION

The FIGURE is a front view of an electronic device display screen with graphical user interface for financial instrument tracking.

The broken lines showing of the display screen of an electronic device with graphical user interface illustrate environment and form no part of the claimed design. The broken lines within the graphical user interface illustrate elements of the graphical user interface that form no part of the claimed design.
